UNITED STATES PATENT OFFICE.

ROBERT FELLONS GOWEN, OF NEW YORK, N. Y., ASSIGNOR TO DE FOREST RADIO
TELEPHONE & TELEGRAPH COMPANY, OF NEW YORK, N. Y., A CORPORATION
OF DELAWARE.

INDUCTANCE-COIL MOUNTING.

1,365,170.

Specification of Letters Patent. Patented Jan. 11, 1921.

Application filed August 20, 1919. Serial No. 318,631.

To all whom it may concern:

Be it known that I, ROBERT F. GOWEN, a citizen of the United States, residing at New York, county and State of New York, have 5 made a certain new and useful Invention in Inductance - Coil Mountings, of which the following is a specification.

This invention relates to inductance coil mounting and particularly to coils of this 10 nature employed for coupling purposes in the radio art.

The object of the invention is to provide an inductance coil mounting of the character described which is simple, efficient and 15 economical to manufacture.

A further object of the invention is to provide means associated with the loose coupling feature of the structure which will permit ready plugging in or taking out of 20 the inductance coil element.

Further objects of the invention will appear more fully hereinafter.

The invention consists substantially in the construction, combination, location and 25 relative arrangement of parts, all as will be more fully hereinafter set forth, as shown by the accompanying drawings, and finally pointed out in the appended claims.

Referring to the drawings: 30 Figure 1 is a view in perspective of a loose coupling inductance coil mount embodying my invention.

Fig. 2 is a view in side elevation of the coil.

Fig. 3 is a view in perspective similar to Fig. 1 showing the different form of mount and a three coil structure with two of the coils removed.

Fig. 4 is a similar view showing a modified form of mount with a two coil structure.

The same part is designated by the same reference character wherever it occurs throughout the several views.

Where a loose coupling is desired between 45 the inductance coils and especially in the radio art, it is customary to vary the position of the coils relative to each other by hand, moving one coil relative to the other and rely on the weight of the coils to prevent further movement. This movement is unsatisfactory in that a jar to the panel supporting the coils or the table on which the coils are laid frequently causes the adjustment thereof to become disturbed. Further, 50 a fine adjustment of the space between the

inductance coils frequently required, especially in radio work, is difficult to obtain in this manner.

It is among the several purposes of my present invention to overcome these objections and to provide mechanical means for adjusting a coupling between inductance coils which will permit a fine degree of adjustment and permanency of adjustment once obtained. 60

While I have shown and will now describe inductance coil mountings especially designed for radio work, I desire it to be understood that I do not intend to limit or restrict the invention to this specific use 70 as the same may be applied wherever loose coupled coils can be utilized. 65

In Fig. 1 of the drawings I show a mounting applied to a flat base 1 adapted to rest on a flat surface such as a disk, table 75 or the like, where the balance of the apparatus is stationed. Secured in any suitable manner to the base 1 is a standard 2 for supporting the coil mount which consists of a bracket 3 in which is readily secured a member 4 having male and female electrical plugs 5 and 6 respectively. The stationary member 4 is disposed centrally in the bracket 3 and on each side thereof extending through the arms of the bracket are shafts 7 and 8 85 on which are mounted to rotate therewith members 9 and 10, each provided with male and female conducting plugs 5 and 6 respectively similar to the structure of the stationary plug 4. Mounted on the shafts 80 6 and 7 are gear wheels 11, which gear wheels mesh with gear wheels 12 mounted on the shaft 13 which is rotatable, extending through the bracket 3 and is provided at its upper end with a knob 14. From the foregoing it will be seen that upon rotation of either unit 14 manually or otherwise the rotatable member 9 or 10 is moved about its 90 pivot to the desired degree. The inductance coils are illustrated at 15 and are shown as 100 of the self-supporting type, that is, they are cylindrical and are secured to the coil bracket 16 by means of a strap 17 screwed into the member 16. The member 16 is provided with the male and female plug members 18 and 19 105 respectively so that to connect the inductance coils in their operative position it is merely necessary to plug in the inductance coil structure so that the male and female members of the respective plugs may engage each 110

other. I make no claim in this present application to the structure of coil or the strap support therefor as the same forms the subject matter of separate applications for patents therefor. In the illustration of Fig. 1 to show the structure of the member 4 the central inductance coil has been slightly withdrawn from its operative position. The structure of Fig. 3 is similar to that of Fig. 1, the only difference being that the structure is set up on a vertical panel rather than on a horizontal one. It will be understood that the terminals of the respective coils are in electrical connection with the respective male and female plugs 18 and 19 in each instance and that the male and female terminals 5 and 6 of the members 4, 9 and 10 are in electrical connection with wire terminals to afford circuital connection with the balance of the circuits in the system. These terminals are illustrated in Fig. 1 at 20 and in the vertical panel arrangement of Fig. 3 the terminals are located in the rear of the panel 21.

It will be understood that any number of coils may be used according to the use to which the system is to be put. For example a single radially disposed coil may be employed or one movable coil with a stationary coil as illustrated in Fig. 4 or a centrally stationary coil and a manually movable coil on either side of the same as illustrated in Figs. 1 and 3.

If desired the gear wheel movement may be eliminated as illustrated in Fig. 4. In this arrangement the stationary member 4 is radially secured in the bracket 3 as hereinbefore described and the movable member 30 mounted on the shaft 31 as above explained is rotated after the coil 15 is inserted in place through its coöperating male and female plug terminals in a manner which will be clearly understood.

Many modifications and changes may be made in the structure set forth without departing from the spirit and scope of my invention as pointed out in the appended claims. Therefore, having set forth the objects and nature of my invention, and a structure embodying the principles thereof, what I claim as new and useful and of my own invention and desire to secure by Letters Patent is:—

1. In an inductance coil mounting, the combination with a support, of a stationary member carried thereby, and a rotatable member carried by said support and positioned adjacent said stationary member, and means for detachably securing inductance coils to said members to form rigid units therewith.
2. In an inductance coil mounting, the combination with a support, of a stationary member carried thereby, and a rotatable member carried by said support and posi-

tioned adjacent said stationary member, means for detachably securing inductance coils to said members to form rigid units therewith, and manually operated means for rotating said rotatable member. 70

3. In an inductance coil mounting, the combination with a support, of a stationary member carried by said support, and rotatable members also carried by said support and positioned adjacent said stationary member, one on each side thereof, and means for detachably securing inductance coils to said members to form rigid units therewith. 75

4. In an inductance coil mounting, the combination with a support, of a stationary member carried by said support, and rotatable members also carried by said support and positioned adjacent said stationary member, one on each side thereof, and manually operated means for rotating said 80 rotatable members independently of each other. 85

5. In an inductance coil mounting, the combination with a support, of a stationary member carried by said support, and rotatable members also carried by said support and positioned adjacent said stationary member, one on each side thereof, and means for detachably securing inductance coils to said members to form rigid units 95 therewith, and manually operated means for rotating said rotatable members independently of each other. 90

6. In an inductance coil mounting, the combination with a support, of a stationary member carried by said support, rotatable shafts journaled in said support and positioned adjacent said member, one on each side thereof, auxiliary members carried by said shafts, to rotate therewith, and means 100 for rotating said shafts independently of each other. 105

7. In an inductance coil mounting, the combination with a support, of a stationary member carried by said support, a rotatable shaft journaled in said support, and positioned adjacent said member, an auxiliary member carried by said shaft for rotative movement therewith, a gear wheel also carried by said shaft, a second shaft carried by 110 said support and provided with a gear wheel engaging said first mentioned gear wheel, and means for rotating said second shaft. 115

8. In an inductance coil mounting, the combination with a support, of a stationary member carried by said support, a rotatable shaft journaled in said support and positioned adjacent said member, an auxiliary member carried by said shaft for rotative movement therewith, means for detachably 120 securing inductance coils to said members to form rigid units therewith, and means for rotating said auxiliary member. 125

9. In an inductance coil mounting, the combination with a support, of electrical 130

terminal members carried thereby and positioned adjacent each other, means for detachably securing inductance coils to said members to form rigid units therewith, and means for moving one of said terminal members relative to the other.

10. In an inductance coil mounting, the combination with a support, of a plurality of terminal members carried thereby, means

for detachably securing inductance coils to 10 said members to form rigid units therewith, and means for independently moving said members relative to each other.

In testimony whereof I have hereunto set my hand on this 6th day of August, A. D. 15 1919.

ROBERT FELLONS GOWEN.
